CLAIM

The ornamental design for a footwear, as shown and described.

DESCRIPTION

FIG. 1 is a right side elevation view of a footwear according to our new design;

FIG. 2 is a front, right side perspective view thereof;

FIG. 3 is a rear, right side perspective view thereof; and, FIG. 4 is an enlarged view of the area labeled "4" in FIG. 1. The evenly-spaced broken lines shown in the drawings illustrate portions of the footwear that form no part of the claimed design. The unevenly-spaced broken lines shown in the drawings represent a boundary that forms no part of the claimed design.
